BOTTLE

Willard R. Horne, Northvale, N.J., and George T. Lloveras, Spring Valley, N.Y., assignors to The Procter & Gamble Company, Cincinnati, Ohio, a corporation of Ohio

Filed Aug. 29, 1968, Ser. No. 13,319

Term of patent 14 years

Int. Cl. D9—01

U.S. Cl. D9—115

FIGURES 5 to 8 inclusive, are cross-sectional views thereof taken on the lines 5—5, 6—6, 7—7 and 8—8 of FIGURE 1 respectively.

The sides opposite FIGURES 1 and 2, respectively, are the same as the sides shown.

I claim:

The ornamental design for a bottle, as shown and described.
